UNITED STATES PATENT OFFICE.

GEORGE B. GARDNER, OF HAVERHILL, MASSACHUSETTS, ASSIGNOR TO UNITED SHOE MACHINERY COMPANY, OF PATERSON, NEW JERSEY, A CORPORATION OF NEW JERSEY.

SHOE-TURNING MACHINE.

1,140,454.

Specification of Letters Patent. Patented May 25, 1915.

Application filed April 16, 1909. Serial No. 490,375.

To all whom it may concern:

Be it known that I, GEORGE B. GARDNER, of Haverhill, county of Essex, State of Massachusetts, have invented an Improvement in Shoe-Turning Machines, of which the following is a specification.

This invention relates to certain improvements in automatic machines and more particularly to such machines having tools which are especially adapted for turning the shoe forepart.

While various devices have been produced for turning shoes, some of which I have myself produced, so far as I am aware these devices have never been used to a material extent, or have not been found to be sufficiently practical to answer the requirements of the trade. Furthermore, these devices, so far as I am aware have been operated by hand or by foot power. One of the objections to a machine which is operated by foot power is that the operator needs to give practically his entire attention to the parts which directly operate upon the shoe and to manipulate the shoe with his hands during the operation, so that the strain on the shoe will be lessened to the greatest extent possible, which he cannot do if he is at the same time pressing down a treadle with the force necessary to perform the turning operation, particularly in view of the fact that the force necessary, in most instances, to perform the operation is quite as much as it is practicable for a man to exert in the ordinary range of a treadle. In devices for this purpose, so far as I am aware, the turning operation has not been accomplished without considerable strain or pull upon the upper, which is an objection, as it pulls the shoe out of shape, or stretches it where it ought not to be stretched, sometimes seriously damaging the shoe.

The object of my invention is to provide a shoe turning machine with means whereby it may be operated by power, but which may nevertheless be at all times under the direct and immediate control of the operator.

A further object is to provide a machine for turning the forepart of shoes, which will imitate as closely as practicable, the hand manipulation which is necessary to

perform this operation, and further, which will perform this operation practically without undue strain upon the upper. 55

To the accomplishment of these objects and such others as may hereinafter appear, as will be readily understood by those skilled in the art, the invention comprises the features and combinations of parts hereinafter described and particularly pointed out in the appended claims.

The best form of the invention at present known to me is by the means shown in the accompanying drawing, in which, 65

Figure 1 is a front elevation of a turning machine made according to my invention. Figs. 2, 3, 4, 5 and 6 are side elevations thereof, showing the parts in different positions. Fig. 7 is a sectional view on the line *a—a* of Fig. 1. Fig. 8 is a detail sectional view of one of the stopping fingers. Figs. 9, 10 and 11 are detail views of the treadle locking-mechanism. Fig. 12 is a sectional plan view on the line *b—b* of Fig. 1. 75 Fig. 13 is a detail view of a portion of the bending finger operating mechanism. Fig. 14 is a detail view of a portion of the clutch. Fig. 15 is an enlarged sectional view on line *c—c* of Fig. 1. Figs. 16 and 80 17 are detail views of the stop adjusting means, Fig. 16 being a sectional view on the line *d—d* of Fig. 17. Figs. 18 and 19 are enlarged detail views showing the operation of the sole-bending fingers. Figs. 20 85 and 21 are detail sectional views of the clutch mechanism taken at the line *e—e* of Fig. 12. Fig. 22 is an end view of one of the clutch members. Fig. 23 is a detail view of the treadle mechanism. Fig. 24 is a detail 90 sectional view on the line *f—f* of Fig. 4. Fig. 25 is a detail sectional view of the presser plate supporting means, on line *g—g* of Fig. 19.

As shown in the drawing, I provide a 95 main frame 1, in which a main shaft 2 (Figs. 2 and 12) is journaled, said shaft extending the entire width of the machine, and a shaft 3, which is journaled in the frame in the rear of and parallel to the shaft 2. A pulley 100 4 and gear 5 are mounted on said shaft 3, said gear being arranged in mesh with a gear 6, secured on a sleeve 7, the latter being rotatably mounted on the shaft 2. A disk

- 8 (Figs. 12, 14, 20 and 21), having a pair of axially extending and diametrically disposed lugs 9 mounted in the face thereof, is also mounted on the sleeve 7, said lugs having engaging faces 9' on the ends thereof, which extend obliquely rearward with relation to the direction of rotation, and face in the direction in which they are rotated by the pulley 4, see Figs. 14 and 21.
- 13 In practice the number of these lugs or teeth 9 is greatly increased, two only being shown to avoid complication. A disk 10, having its hub 10' rigidly secured on the shaft 2, is arranged adjacent the disk 8, with its face 15 out of contact with the ends of lugs 9, and a pair of angle levers 11 are pivoted at diametrically opposite points on said hub 10'. The arms 11^a of said levers 11 extend longitudinally of the shaft 2 and are normally 20 drawn toward opposite sides of the shaft by a connecting spring 12, while the opposite arms 11^b extend radially adjacent the periphery of disk 10, and are normally held in a retracted position with relation thereto 25 by said spring 12. A pair of dogs 13 are mounted in said disk to slide perpendicularly thereto, or axially with relation to the main shaft, said dogs being respectively connected to the ends of the arms 11^b and being 30 adapted to be moved thereby from their normal positions, in which the opposite ends thereof from said arms are flush with the face of said disk 10, next disk 8, into the path of movement of lugs 9. Said ends of 35 said dogs are provided with obliquely disposed faces 13' (Fig. 14) arranged oppositely to the faces 9' and at an angle which is the complement of the angle of faces 9', so that when said dogs are moved from the 40 position of Fig. 20 to the position of Fig. 21, or from the full line to the dotted line position of Fig. 14, said faces 13' will be engaged by said faces 9' and said shaft 2 will be driven from the pulley 4, which, in 45 practice, is constantly driven in the direction of the arrow in Fig. 2.

The above described clutch-mechanism is operated by the following means. A sleeve 14 (Figs. 12, 20 and 21) is splined on the shaft 2, said sleeve being provided with a conical end portion 14^a, on which the arms 11^a are adapted to rest, so that, when said sleeve is moved toward the clutch, said arms 11^a will be moved outwardly to throw the clutch members into engagement. A ring 14^b is swiveled on said sleeve and provided with diametrically arranged pins 14^c, and a radially projecting arm 14^d (Fig. 23) is secured on the end of said sleeve opposite its conical end, in position to engage, in certain positions thereof, an arm 14^e (Figs. 1 and 12) mounted on the frame and having an inclined end 14^f. A bell crank lever 15 (Figs. 20 and 21) is pivoted at 15^a upon the frame, said lever comprising vertically dis-

posed forks 15^b, and a horizontally disposed arm 15^c, the upper ends of said forks being slotted to receive pins 14^c on the ring 14^b. A treadle 16 (Figs. 2 and 23), having an integral sleeve 16^a, is mounted on a pivot rod 70 16^b fixed in the frame, and an arm 17 is secured on said sleeve and is arranged to extend beneath the under side of the horizontal arm 15^c, in position to engage the same after the treadle has been depressed to a 75 certain extent, see Fig. 23. A spring 18 is coiled about the sleeve 16^a, and one end thereof is engaged with a stationary rod 19 on the frame, and the other end thereof is extended rearwardly and rests on the upper 80 side of the arm 15^c, so that said spring acts normally to hold the sleeve 14 in the withdrawn position with relation to the clutch operating levers 11, as shown in Fig. 20.

A segment 20 (Figs. 1 and 2), provided 85 with suitably spaced ratchet-teeth 20', is rigidly secured to the inner side of the disk 10, said teeth being circularly arranged with relation to the shaft 2, and a dog 21 is slidably mounted in the frame in position to 90 engage said teeth 20', in certain positions thereof. Said dog is pivoted to the middle portion of a lever 22, which is connected to the frame by a pivot 22^a at one end, see Figs. 1 and 12, and, at its opposite end, is adapted 95 to be engaged by the upwardly extending arm 23 (Fig. 2) of a bell crank lever, pivoted at 23^a, the horizontal arm 23' of said lever extending over the upper end of a vertically disposed finger 24 rigidly mounted 100 on the treadle 16. A spring 25 is connected to said lever 22 and to the frame, and is adapted to swing the lever 22 toward the rear, so as to force the dog 21 into engagement with the ratchet segment 20. A supplemental lifting spring 26 (Fig. 12) is connected to the treadle 16 and, acting in conjunction with the spring 18, normally holds the treadle in the raised position of Fig. 2, in which position the finger 24, acting on the 110 lever arms 23', 23, throws the lever 22 outwardly and thereby holds the dog 21 out of engagement with said ratchet.

As best shown in Figs. 9, 10 and 11, a spring actuated bolt 27 is mounted on the 115 under side of the treadle 16, and is constantly held against the side of a bracket 28, which extends vertically at one side of the treadle, and a notch 28' is formed in one side of said bracket, which said bolt is 120 adapted to enter, automatically, in one position of the treadle. A tripping dog 29 is pivotally mounted at 29^a upon the bracket 28, and normally rests by gravity in a horizontal position against stop pins 30, on 125 said bracket, in which position the end of said dog next the treadle extends opposite said notch. Said dog has an engaging face at its said end, which extends obliquely outward and upward from the side of bracket 130

28, when in its normal position. With this arrangement, when the treadle is depressed from its normal position, shown in Fig. 9, the bolt 27 will engage the upper side of 5 the projecting end of dog 29 and press said end downwardly, so that said bolt may enter the notch 28^a, as shown in Fig. 10, and hold the treadle from upward movement. On further depression of the treadle 16, said 10 bolt 27 will be moved out of the notch 28^a and will be carried past said dog 29, so that the latter by gravity returns to its former position, as shown in Fig. 11, so that, when the treadle is raised from this position, the 15 end of said bolt 27 will be engaged by the inclined end face of the dog 29, which will press said bolt 27 back from the bracket 28, and hold it out of engagement with the bracket until it is carried above the notch 20 28^a, thereby preventing said bolt from becoming reengaged therein.

The main shaft 2 is provided with a crank 32 (Figs. 1 and 2), formed by providing right angular bends therein, and with a crank- 25 arm 33, the angles between said cranks being slightly more than 90°. A connecting rod 34 (Figs. 3, 4 and 6) is pivoted at its lower end to the crank 32 and at its upper end to an intermediate portion of a lever 35, 30 said lever 35 being pivotally mounted at its rear end on the frame and pivotally connected at its front end to one end of a link 36. The other end of link 36 is pivoted to the lower end of a rod 37, which extends 35 vertically through the table 1^a of the machine, and is adapted to slide in a guiding boss 1^b integral with the table. A forepart turning post 38 is mounted on the upper end of said rod 37, said post extending vertically and being provided with a corrugated 40 roll 39, at its upper end. The rear side of said post is vertical and the front side is slightly inclined rearwardly as it extends upwardly, and is similar to the ordinary 45 turning-post or toe-stick employed in turning shoes by hand. A link 40 is connected at its lower end to the crank 33, and at its upper end to the lower end of a second link 41, the connection between said links 40 and 50 41 comprising a bolt 42 mounted in the link 41 which passes through a slot 40^a in the link 40, to permit a certain amount of lost motion therebetween. Said link 41 is forked at its upper end, and a nut 41^a is pivotally mounted 55 between the forked portions thereof. A rod 43 is threaded into said nut 41^a and extends vertically therefrom through the table 1^a, the upper end of said rod 43 being pivoted to one end of an arm 44, which is there- 60 by adapted to swing in a vertical plane from front to rear, between guiding fingers 44^a mounted on boss 1^b. The opposite end of arm 44 is provided with a right angularly bent portion on the extreme end of which a 65 transversely extending clamping head 45 is

pivotsly mounted, said head having a leather face 46 at the opposite side thereof from the side which is pivotally connected to said arm. A friction roll 44^a is mounted on the front side of the arm 44 adjacent the 70 point at which it is connected to the link 43. The rear side of said lever 44, adjacent the end thereof which is connected to the rod 43, is adapted to rest in the peripheral groove of a roll 47 (Fig. 7), which is rotatably mounted 75 on a shaft 47^a, mounted in a bracket 48, supported on the table 1^a of the frame and adapted to slide in ways 48^a mounted on the table, from front to rear and in the plane in which the lever 44 is adapted to swing. 80 A link 49 is pivoted at one end to shaft 47^a and at its other end to a hand lever 50 (Fig. 2), which is pivoted on a bracket 50^a on the table.

A rod 51 having ears 51^a at its front end, 85 through which the shaft 47^a passes, is mounted to slide in a bracket 51^a fixed on the table, and a spring 52 is mounted on said rod 51 between said bracket and a shoulder formed at the base of the ears of said rod, so that 90 said spring acts to resist rearward pressure on the roll 47, which is thereby enabled to act as a yielding fulcrum for the arm or lever 44. A pair of springs 41^b (Fig. 3) are connected to the upper end of link 41 and 95 act to hold lever 44 normally in the position of Fig. 2.

A rod 53 (Figs. 2 and 6) is adjustably mounted, at its lower end, on the rod 43 and extends parallel thereto upwardly 100 through the table, and at its upper end is provided with a sole engaging head 54, said head having a clamping face adapted to conform to the face 46 on the head 45, the head 54 also having a projection 54^a, which extends downwardly and rearwardly, at the lower end thereof, and a series of downwardly extending hooked-shaped teeth 54^b. In the normal position of the post 38 the upper end thereof is approximately at the 110 same level or slightly below the upper end of the head 54, as shown in Fig. 2.

A crank arm 55 (Fig. 2) is connected to the shaft 2 and a link 56 is connected at one end to said arm 55, and at its other end to an intermediate portion of a lever 57 which is pivoted at its front end on a cross bar 57^a. A cylinder 58 is pivotally mounted on the frame in the rear thereof and a piston-rod 59, having a piston 59^a at its lower end, is 115 adapted to reciprocate therein, said piston being pivotally connected at its upper end to the rear end of the lever 57. Said cylinder 58 is provided with any convenient means for permitting a ready ingress and 120 restricted egress of air at its lower end, as the check valve 58^a and adjustable cock 58^b, indicated in dotted lines in Fig. 2.

A strap 60 (Figs. 1 and 12) is connected 125 at one end to a grooved pulley 61, mounted

on the left hand end of the shaft 2, in position to be wound about said pulley, and at its other end to one end of a coiled spring 62, said spring being connected at its other end 5 to the frame and the arrangement being such that when the shaft 2 is advanced said strap will be wound upon said pulley, and when said shaft is released said spring 62 may act to reverse the rotation of the shaft.

10 A pair of bracket arms 63 (Figs. 1 and 6) are mounted on the boss 1^b and extend horizontally forward therefrom and a square holding block 64 is pivotally mounted between said arms. A supporting rod 65 (Fig. 1) passes through, and is secured in said block 64, said rod extending vertically in front of the machine and being adapted to swing in the plane of the post 38 and lever 41. A pair of brackets 66 and 67 are secured on the rod 65 adjacent the upper and lower ends thereof, and a pair of operating rods 68 and 69 are mounted therein equidistant from and at each side of rod 65, and are adapted to move longitudinally and rotatably with relation thereto. Said rods 68 and 69 are provided with two right angular bends in the upper ends thereof, providing rearwardly extending arms 68^a and 69^a (Figs. 1, 18 and 19) and upwardly extending fingers 68^b and 69^b, said fingers being slightly inclined rearwardly from the perpendicular, so that the sides thereof are approximately parallel with the sides of the post 38 adjacent and at each side of which 35 they are located.

15 A pair of arms 70 and 71 (Figs. 2 to 6 and 15) are secured on the upper forked end of the link 41, and said arms extend horizontally forward and are each provided 40 with forked ends 70^a, 71^a, between which the rods 68 and 69 respectively pass, and said rods 68 and 69 are each provided with a pair of collars 68^c, 68^d and 69^c, 69^d (Fig. 1) respectively, above and below said forks 45 70^a and 71^a, the latter being adapted to engage said collars and limit the longitudinal movement of said rods 68 and 69 with relation to said forks, while permitting the same to swing with said rod 65. A bracket 50 72 is mounted on the lower end of the rod 65, see Figs. 1 and 24, and is provided with transverse ears 72^a and 72^b which are adapted to engage the rear sides of the rods 68 and 69 adjacent their lower ends, and said 55 bracket is also provided with a groove 72^c, which is adapted to receive one edge portion of a wedge-shaped cam 73 (Figs. 3, 4 and 6), the latter being arranged with its apex end down and the opposite edge portion 60 thereof being adapted to enter the peripheral groove of a roll 74 (Fig. 13) rotatably mounted on a cross-rod 74^a in the frame. A link 75 is connected at its upper end to the lower end of the cam 73, and at its 65 lower end is eccentrically connected to a wheel 76 rotatably mounted on a shaft 76^a supported in a bracket 76^b on the frame, see Fig. 12. A link 77 is also eccentrically connected at its upper end to the wheel 76 at a point about 90° from the point of connection of link 75 therewith, and, at its lower end, to the end of an arm 78 (Figs. 2 and 23) on the treadle sleeve 16^a, the parts being so arranged that when the treadle 16 is depressed, drawing said arm 78 downwardly, 75 the wheel 76 will be caused to make a partial revolution, thereby drawing down the cam 73 and causing the bracket 72 to be forced outwardly and said fingers 68^b, 69^b to be swung rearwardly (see Figs. 3 and 4). 80

10 A pair of arms 79 and 80 (Figs. 1 and 13) are adjustably mounted on the rods 68 and 69, respectively, adjacent the lower ends thereof, said arms being longitudinally curved and arranged to extend divergently 85 rearward between a pair of vertical fingers 81 and 82, adjustably secured on the transverse rod 74^a, secured to the frame. Springs 84 and 85 are respectively connected to the arms 79 and 80 and to the frame and act to 90 hold the sides of said arms 79 and 80 constantly in engagement with the fingers 81 and 82 respectively.

15 A pair of guiding fingers 86 (Fig. 1) are mounted on the rod 57^a, between which the 95 rod 65 is adapted to be swung, and a spring 87 (Figs. 3 and 4) is connected to the rod 65 and to the rod 57^a and acts to hold the bracket 72 constantly in engagement with the cam 73. 100

20 A bracket 38^a (Figs. 1 to 6) is rigidly mounted on the front side of the post 38 and extends horizontally forward therefrom, midway between the rods 68 and 69 and a vertical rod 88 is rigidly mounted 105 in the front end of said bracket. As shown in detail in Fig. 25, a collar 89 is adjustably mounted on said rod 88 and a horizontal supporting rod 90 is rigidly mounted in said collar and extends rearwardly from said rod 88. A sleeve 91 is slidably mounted on the end of said rod 90 and is connected thereto by means of a pin 90^a mounted in the end of the rod, said pin being located in a pair of longitudinal slots 91^a in said sleeve, 110 said pin thereby acting to hold said sleeve from rotation and limiting the sliding movement thereof on said rod. A holding plate 92 is mounted on the rear end of the sleeve 91 in a nearly vertical position, and a 115 spring 90^b is arranged on said rod 90 and sleeve 91, between said collar 89 and the plate 92, said spring being adapted to press said plate rearwardly and the parts being so arranged that said plate will be normally 120 held at a short distance from the post 38, as shown in Fig. 2. The plate is transversely concaved in its middle portion and longitudinally convex at its end portions, 125 its side edges being reversely curved and 130

convexly formed, so that the entire edge portion thereof flares away from the post 38, as shown in Figs. 18, 19 and 25.

A vertical rod 93 (Figs. 2 to 6) is mounted to slide longitudinally in the brackets 38^a and 63 directly in front of the post 38 and a spring catch 93^a is mounted on the bracket 63 in position to engage a series of longitudinal corrugations on said rod 93 to permit the same to be locked in the various vertical positions to which it may be adjusted. A gage-plate 94 (Fig. 18) is mounted in a horizontal position on the upper end of the rod 93 and extends in close proximity to the post 38.

A bell crank lever 95 (Figs. 1 and 12) is pivotally mounted on the frame directly above the shaft 2, said lever having a pair of vertically disposed arms 95^a which are adapted to extend on opposite sides of the clutch sleeve 14, in position to engage the annular shoulder 14^a on said sleeve at the end of the conical portion 14^a thereof. The other arm 95^b of said lever extends horizontally and is connected at its outer end to one end of a link 96 (Figs. 1 and 2), the opposite end of said link being connected to one end of a lever 97 (Figs. 1 and 7) pivotally mounted on the table. A vertically extending rod 98 is adjustably mounted in the opposite end of said lever 97, at right angles thereto, and, to provide for a convenient means for locking said rod in various positions of adjustment, said rod is provided with a longitudinal series of teeth 98^a, (see Figs. 16 and 17), and a thumb lever 99 is mounted on said lever 97, and is provided with a dog 99^a at one end thereof, which is adapted to engage the teeth 98^a of the rod 98, and a spring 99^b at the other end thereof, which is adapted to hold said dog in engagement with said teeth. A series of fingers 100, of regularly increasing length, are arranged one above the other on the upper end of the rod 98, and are adapted to swing thereon through an arc of 90°, each finger being provided with means for holding it by frictional engagement in the two positions to which it may be moved, said means each comprising a spring-pressed dog 101, (see Fig. 8), mounted in a recess in the rod 98, in position to engage the bearing surface of the finger, which is provided with recesses about 90° apart, which said dog is adapted to enter. As a finger 100 is turned from one position to the other, as indicated in Fig. 8, the dog will be pressed inwardly, thereby causing frictional resistance to said movement, which, however, is not sufficient to prevent ready movement of the finger, but is sufficient to hold it in either position to which it may be moved. A rod 102 is pivotally mounted at its lower end to the lever 35 and extends upwardly through an opening in the table of sufficient size to permit said rod to

be raised longitudinally and approximately vertically when said lever 35 is swung upward, said rod being provided with a horizontally extending finger 103 at its upper end which is arranged to extend directly beneath said fingers 100 when swung toward the front, so that when said rod 102 is forced upwardly by the upward swinging movement of the lever 35 said finger 103 will engage whichever of the fingers 100 as may have been moved in the path thereof, thereby causing said lever 97 to be moved so as to force said link 96 downwardly, and said lever 95 to be swung so as to move the clutch sleeve 14 away from the clutch, to disengage the clutch members.

The operation of the machine above described is as follows: When the parts are in the initial position of Figs. 1 and 2, all the parts are stationary except the clutch member 8 and the intermediate mechanism, the pulley 4 being constantly driven in the direction of the arrow in Fig. 2. The first step in the turning operation of the forepart of the shoe, the heel part of which has been previously turned, is to place the shoe forepart toe downward in a vertical position between the plate 92 and the front side of the turning-post 38, with the sole against the post and the ball of the shoe approximately opposite or bearing against the roll 39 in the upper end of the post.

For the purpose of enabling the shoe to be placed readily in the exact vertical position desired, when several shoes of the same size are to be turned, the gage-plate 94 is so adjusted that the toe of the shoe will rest against said plate when the shoe is in the correct position for turning. The shoe is held in this position by the operator, with his hands, and he then depresses the treadle 16 until the spring-pressed bolt 27 enters the notch 28^a, as shown in Fig. 10, in which position the treadle will be held from returning. This movement of the treadle causes the arm 78 to be swung downwardly and the arm 17 to be swung upwardly until it touches the under side of the bell crank lever arm 15^a. The downward movement of the arm 78 causes the link 77 to be drawn downwardly, which causes a partial rotation of the wheel 76, and causes the cam 73, through the medium of the link 75, to be drawn downwardly. The downward movement of the cam 73 causes the lower ends of the rod 65, 68 and 69 to be swung forwardly, so that the upper ends thereof will be swung rearwardly on the pivot block 64 as a center. This movement also causes the rods 68 and 69 to make a partial rotation toward each other, for, as the divergently curved arms 79 and 80 are drawn forwardly by the forward swinging movement of the rods 68 and 69, they will also be swung toward each other by the sta-

tionary fingers 81 and 82 against which they are drawn. The fingers 68^b and 69^b are, therefore, caused to move obliquely rearward or convergently toward the sides 5 of the post 38. The initial position of said fingers is shown in Fig. 18, in which position the sole of the shoe is held approximately flat. The formation of the arms 79 and 80 is such that the initial movement of 10 said fingers is rearward, during which movement they engage the shoe adjacent its edges, at the opposite sides of the post, 38 and press the same rearwardly, so that the sole is bent longitudinally, or from end to 15 end. During the further rearward movement of said fingers, they are also moved toward each other, so that they also act to press the side edge portions of the sole closely about or against the sides of the 20 post 38, bringing the side edges of the sole in sufficiently close proximity throughout nearly the entire length of its forepart, and particularly at the widest, or ball portion, to permit the turning operation to be performed to the best advantage.

The fingers 68^b and 69^b are locked in this position by the treadle, which is held from rising by the bolt 27, so that the operator is then free to adjust the shoe on the turning post to the best advantage, without holding his foot on the treadle. While the shoe is held in this position, illustrated in Fig. 3, the operator then bends the heel part 30 of the shoe rearwardly and downwardly, over the end of the post 38, so that the sole is bent sharply across the same, at the ball, the heel portion of the sole being swung down against the face of the head 54, and the counter portion of the shoe being passed 35 over the lower projecting end 54^a of said head. The operator then pulls downwardly on the sides of the upper, so that the ball portion of the shoe is turned and the shoe is held in the position of Fig. 4. The operator then further depresses the treadle, moving it below its locked position, causing the lever 15 to be swung, so as to advance the clutch sleeve 14, moving the clutch levers 40 11, so that the dogs 13 are moved outwardly 45 beyond the face of the disk 10, in which position the oblique faces thereof will be engaged by the oblique faces of the lugs 9, on the constantly rotating disk 8, so that the shaft 2 will be driven forwardly, against 50 the action of the returning spring 62 which is stretched by the winding of the strap 60 on pulley 61, said shaft being driven at a low rate of speed, so that the operation will not be advanced any faster than is desired 55 by the operator. In the initial position of the parts the crank 32 is held approximately in its lowest position, so that the first part of the movement of said crank practically causes nothing more than a swinging movement 60 of the link 34. The crank 33 is, how-

ever, held at slightly more than 90° from the crank 32, so that the downward movement thereof immediately causes a downward pull on the link 40, which causes the bolt 42 to be engaged by the link 40, at the upper end of the slot 40^a, of said link, and continued movement of the shaft causes the links 40 and 41 to be drawn downwardly, and with them the rod 43, thereby causing a downward pull on the front end of the lever 44. As the lever 44 rests on the roll 47, the latter will act as a fulcrum, so that the lever will be thrown forwardly until its roll 44^a engages the rod 53, and the head 45 is carried into coöperative relation with the head 54. As the heel part of the sole has been bent down over the face of the head 54, the sole will be firmly clamped between said head 54 and the head 45, as shown in Fig. 4. As said head 54 is provided with hook-shaped teeth 54^b and also an outwardly bent lip 54^a at its lower end, which bends out the heel seat of the sole about the lower end of the head 45, any upward or longitudinal pull on the sole will be effectively resisted. It will be noted in this connection that the grain or outer side of the sole will be engaged by the leather face of head 45, so that no injury will be done to the portions of the sole which will be exposed.

Depression of the treadle 16 to the locked position of Fig. 10, lowers the finger 24 out of engagement with the arm 23', so that the spring 25 is permitted to force the dog 21 into engagement with the ratchet segment 20, and, when the parts are moved into the position of Fig. 4, the dog 21 will have been moved into engagement with the first tooth of the segment 20. If it is desired to arrest the turning operation at this, or any other point, the treadle 16 will be raised sufficiently to permit the dogs 13 to be withdrawn from engagement with the lugs 9, so that the shaft 2 will be disconnected from the driving pulley and the parts will be arrested in their advancing movement and held by the dog 21 in the position to which they are advanced. If it is desired to advance the turning operation still further the treadle is again depressed to an extent sufficient to reengage the main clutch members.

When the operation is advanced beyond the position of Fig. 4, the link 34 is forced upwardly, thereby forcing the post 38 vertically upward. At the same time the clamp members 45 and 54 are drawn downwardly by the further movement of crank 33, drawing down the heel part and thereby not only effectively holding the shoe against the upward push of the post 38, as it performs its turning operation, but also acting to turn the shoe on the post. At the same time the operator may assist the operation by pulling downwardly on the flies or sides of the up-

per of the shoe, the operation being thus advanced as indicated in Fig. 5. It is to be noted that the back side of the clamp member 54 rests against the post 38 as it is drawn down, which thus acts as a support for the clamp, as the pull on the shoe tends to draw the clamp toward the post.

If the fingers 68^b, 69^b were permitted to remain in the position of Fig. 4, they would interfere with, or prevent the rolling down of the upper, as the operation is continued. To obviate this difficulty and yet enable said fingers to perform their function of holding the sole bent longitudinally until the operation is nearly finished, means are provided for lowering the fingers to a sufficient extent to permit the upper to be rolled down without permitting said fingers to move out of engagement with the shoe forepart. This is accomplished in the following manner:— In the initial clamping position of Fig. 3, the upper sides of the forks 70^a and 71^a are in engagement with the upper collars 68^c and 69^c but as the link 41 is drawn down and the parts are moved to the position of Fig. 4, said forks will be moved down into engagement with the lower collars 68^d and 69^d, the frictional engagement of the fingers 68^b and 69^b being sufficient to prevent said rods 68 and 69 falling down by gravity. Further downward movement, therefore, of the link 41 will cause said rods 68 and 69 to be drawn downwardly at approximately the rate at which said clamp members 45 and 54 are drawn down, so that all possibility of interference of the fingers with the turning operation is avoided, while they will continue to hold the sole in the bent position of Fig. 19. The operation is thus continued until the shoe is finally turned as shown in Fig. 6. During this operation the plate 92 assists the fingers 68^b and 69^b in holding the forepart in the bent position of Fig. 19, and, what is more important, it prevents the toe portion of the shoe from swinging away from the post, during practically the whole operation, the tendency to swing forwardly being caused by the upward movement of the post 38, and the downward pull of the clamp on the rear portion of the sole, which motion, if permitted, would seriously interfere with, if not prevent, the turning of the shoe. The fingers 68^b and 69^b and plate 92 thus perform two highly important functions, first, to bend the sole so that it may be turned and hold it in bent position while it is being turned, and second, to hold the sole forepart close to the side of the post until the operation is nearly finished.

Before the turning operation is begun, the rod 98, in the lever 97, is adjusted vertically to correspond approximately to the size of shoe which is to be turned, that is, according to whether the shoe is a woman's

shoe or misses' or children's, and one of the arms 100 is thrown forwardly, according to the particular size of shoe which is to be turned. The combined adjustment is such that when the shoe is nearly turned the finger 103, which is constantly raised during the turning operation by the upward movement of the lever 35, will be moved into engagement with one of the fingers 100, causing the rod 98 to be drawn upwardly swinging the lever 97, so as to operate the bell crank lever 95 and throw out the main clutch, so that further progressive movement will be prevented, and all danger of the shoe being damaged by the turning post 80 will be avoided.

It will be understood that the turning operation may be arrested at any time by merely relieving the pressure of the treadle 16 to a sufficient extent to permit the main clutch to become disengaged. The inclination of the engaging faces of the clutch dogs 9, and 13 is such that the driving force, in addition to the force of spring 12, constantly tends to force them out of engagement, so that a release of the force which holds the dogs 13 in engagement will cause practically instantaneous release of the clutch members, and thus the progressive movement of the turning devices may be stopped practically 95 instantaneously.

The length of the ratchet segment 20 is such that the dog 21 will be in engagement therewith throughout the movement of the parts from the position of Fig. 4, to the 100 final position of Fig. 6, so that if the treadle 16 is raised only sufficiently to disengage the clutch at any intermediate position, the parts will be held in approximately the position to which they have been advanced. Thus, any 105 return movement by spring 62, beyond the point at which the dog 21 engages the tooth of the segment 20 which has last passed it, is prevented. It may be noted, in this connection, that the slight return movement, which almost invariably occurs before the dog 21 110 engages the next tooth, is of especial advantage, as it relieves the strain, placed on the shoe by the turning devices, sufficiently to permit the operator to readjust the shoe 115 to better advantage and more easily than would be possible if the full strain were placed thereon.

When the operation is completed and the treadle is permitted to be raised to its fullest extent the finger 24 will engage the arm 23' and withdraw the dog 21, permitting the returning spring 62 to return the parts to the initial position of Fig. 2, so that the shoe may be then readily removed.

Inasmuch as, with the construction above described, the shaft 2 cannot be rotated but slightly more than one-quarter of a revolution, I provide the arm 14^a (Fig. 23) on the clutch sleeve 14 which is adapted to engage 130

the inclined face 14^a on the stationary arm 14^a, when the parts have advanced to an extent necessary to turn any shoe which would be likely to be turned upon the machine. 5 When this engagement occurs the arm 14^a will be deflected to the left, carrying with it the clutch sleeve 14, so that the main clutch will be disconnected and further advance movement of the parts will be prevented. 10 During the advancing movement of the parts the crank 55 will lift link 56 which will act to swing the lever 57 upwardly and draw up the piston 59 in the cylinder 58, so that, when the treadle 16 is entirely released, 15 so that the dog 21 is withdrawn from the ratchet segment 20, and the main clutch is disengaged, the speed of the return motion of the parts, which would otherwise be caused by the returning spring, will be arrested by the air resistance in said cylinder.

The hand lever 50 is provided for the purpose of drawing back the pivot roll 47 and thus permitting the clamping head 45 to swing rearwardly, so that the operator 25 may readjust the shoe if he finds it necessary to do so during the turning operation, without making it necessary to return the parts to the initial position.

When the treadle 16 is permitted to rise 30 to its fullest extent, the cam 73 will be raised permitting the spring 87 to swing the rods 68 and 69 so as to withdraw the sole bending fingers from the post 38. When the fingers 68^a and 69^a are moved out of engagement 35 with the shoe, the rods 68 and 69 will fall of their own weight, so that the upper collars 68^c and 69^c will reengage the forks 70^a and 71^a and be again supported thereby.

By adjusting the vertical fingers 81 and 82 40 toward or from each other, the limits of the path in which the fingers 68^b and 69^b shall move may be varied.

In the following claims all references to 45 position, or direction of movement of the elements, are to be interpreted as terms of designation and not of limitation, as obviously it is the relative position or relative direction of movement which alone is of importance.

Nothing herein contained is to be interpreted as limiting the invention in the scope of its application to use in connection with the particular machine, or the particular mode of operation, or both, selected for purposes of illustration and explanation. 50

While the particulars of construction herein set forth are well suited to one mechanical form of the invention, it is not to be understood that these particulars are essential since they may be variously modified within the skill of the artisan without departing from the true scope of the actual invention as defined in the following claims. 60

Having thus described my invention, what

I claim as new and desire to secure by Letters Patent is:—

1. A machine for turning the foreparts of shoes, having, in combination, a forepart turning post, means including a forepart engaging tool for holding the shoe relatively to the post in position to have its forepart turned by the post, and automatic means for relatively moving the post and shoe holding devices operating to turn the forepart without manipulation by the operator, substantially as described. 70

2. A machine for turning the foreparts of shoes, having, in combination, a forepart turning post, means for holding the shoe relatively to the post in position to have its forepart turned by the post, including a forepart engaging tool and a heel clamp, and automatic means for relatively moving the post and heel clamp, whereby the forepart is turned over the post without manipulation by the operator, substantially as described. 80

3. A machine for turning the foreparts of shoes, having, in combination, a forepart turning post, means for holding the shoe relatively to the post in position to have its forepart turned by the post, including a forepart engaging tool and a heel clamp, and automatic means for closing said clamp on the heel and thereafter relatively moving the post and heel clamp, whereby the forepart is turned over the post without manipulation by the operator, substantially as described. 90

4. A shoe-turning machine comprising turning devices, a shaft, operating mechanisms disposed to be actuated by said shaft upon rotation thereof in one direction to move said devices from an initial position, to perform the turning operation, and means for automatically stopping the advance of the turning devices and then rotating said shaft in the opposite direction to return said parts to their initial positions, substantially as described. 100

5. A shoe-turning machine comprising turning devices, power-actuated devices, a controlling device movable to connect said power-actuated devices and said turning devices to move said turning devices from an initial position to perform the turning operation, and means controlled by the advance of the turning device for automatically disconnecting said power actuated and said turning devices to permit said turning devices to be returned to their initial position, substantially as described. 110

6. A forepart turning machine comprising a forepart turning post, power-actuated devices for advancing the post toward the toe of the shoe, a controlling device movable to connect said power-actuated devices and said post to move the post from an initial position to perform the turning operation, 120

- and means connected to be operated by the advance of the turning post for disconnecting said power-actuated devices and stop the advance of the post when it has reached a 5 predetermined position within the forepart, substantially as described.
7. A forepart turning machine comprising a forepart turning post, power-actuated devices for advancing the post toward the toe 10 of the shoe, a controlling device movable to connect said power-actuated devices and said post to move the post from an initial position to perform the turning operation, a tripping mechanism movable to disconnect 15 said post and said power-actuated devices, and an engaging device movable with the post to engage said tripping mechanism to operate the same when the post is advanced to a predetermined position within the fore- 20 part of the shoe, substantially as described.
8. A shoe - turning machine comprising turning devices, power-actuated devices, a controlling device movable to connect said power-actuated devices and said turning de- 25 vices to move said turning devices from an initial position to perform the turning operation, an operating device movable to disconnect said turning and said power-actuated devices, an engaging device connected 30 to said turning devices and movable therewith to engage said operating device to operate the same, and means constructed to permit variation of the position of engagement of said operating device and said en- 35 gaging device, substantially as described.
9. A shoe - turning machine comprising turning devices, power-actuated devices, a controlling device movable to connect said power-actuated devices and said turning de- 40 vices to move said turning devices from an initial position to perform the turning operation, an operating device movable to disconnect said turning and said power actuated devices, and an engaging device connected 45 to said turning devices and movable therewith to engage said operating device to operate the same, said operating device having a series of fingers adapted to be se- 50 parately moved into or out of the path of said engaging device at different points therein, substantially as described.
10. A shoe - turning machine comprising turning devices, power-actuated devices, a controlling device movable to connect said power-actuated devices and said turning de- 55 vices to move said turning devices from an initial position to perform the turning operation, an operating device movable to disconnect said turning and said power actuated devices, and an engaging device connected 60 to said turning devices and movable therewith to engage said operating device to operate the same, said operating device having an arm adjustable thereon in the direc- 65 tion of the path of said engaging device and said arm having a finger thereon disposed to be engaged by said engaging device, sub-stantially as described.
11. A shoe - turning machine comprising turning devices, power-actuated devices, a controlling device movable to connect said power-actuated devices and said turning devices to move said turning devices from an initial position to perform the turning operation, an operating device movable to disconnect said turning and said power actuated devices, and an engaging device connected to said turning devices and movable therewith to engage said operating device to operate the same, said operating device having an arm adjustable thereon in the direction of the path of said engaging device and said arm having a series of fingers thereon adapted to be separately moved into the path of said engaging device at different points therein, substantially as described. 75
12. A shoe - turning machine comprising turning devices having means for advancing the same from an initial position to perform the turning operation, and additional means coöperating with said first named means for holding said turning devices in different positions of advancement, substan- 80 tially as described. 90
13. A shoe - turning machine comprising turning devices, actuating devices for advancing said turning devices from an initial position to perform the turning operation, a controlling device for said actuating devices, and locking devices automatically operated by movement of said controlling devices for holding said turning devices in different positions of advancement, substan- 95 tially as described. 100
14. A shoe - turning machine comprising turning devices having actuating devices for advancing the same from an initial position to perform the turning operation, a controlling device, and means for holding said turning devices in different positions of advancement disposed to be operated by said controlling device, substantially as described. 105
15. A shoe - turning machine comprising turning devices having actuating devices for advancing the same from an initial position to perform the turning operation, a locking device for automatically holding said turning devices in different positions of advancement, means for returning said devices to said initial position and means for controlling said actuating devices and said locking device, substantially as described. 110 115
16. A shoe - turning machine comprising turning devices having actuating devices for advancing the same from an initial position to perform the turning operation, means for returning said turning devices to said posi- 120 125

tion, a controlling device for said actuating devices, a locking device for automatically holding said turning devices in different positions of advancement and means for releasing said locking device disposed to be operated by said controlling device, substantially as described.

17. A shoe-turning machine comprising turning devices having actuating devices for advancing the same from an initial position to perform the turning operation, a locking device for automatically holding said turning devices in different positions of advancement, means for returning said turning devices to said initial position, and a controlling device movable in one direction to control said actuating devices and in the opposite direction to control said locking device, substantially as described.
18. A shoe-turning machine comprising turning devices and actuating devices for advancing the same from an initial position to perform the turning operation, retracting means for returning said turning devices to said position, a locking device for holding said turning devices in different positions of advancement, and a controlling device movable in one direction to cause operation of said actuating devices and movement of said locking device to operative position and movable in the opposite direction to permit operation of said retracting means and to move said locking device to an inoperative position, substantially as described.

19. A shoe-turning machine comprising turning devices, power-actuated devices for advancing said turning devices from an initial position to perform the turning operation, a controlling device for said power-actuated devices, and means for holding said turning devices in different positions of advancement, substantially as described.

20. A shoe-turning machine comprising turning devices, power-actuated devices for advancing said turning devices from an initial position to perform the turning operation, a controlling device for said power-actuated devices, and a locking device for automatically holding said turning devices in different positions of advancement, substantially as described.

21. A shoe-turning machine comprising turning devices, power-actuated devices for advancing said turning devices from an initial position to perform the turning operation, a controlling device for said power-actuated devices, and means for holding said turning devices in different positions of advancement disposed to be operated by said controlling device, substantially as described.

22. A shoe-turning machine comprising turning devices, power-actuated devices for advancing said turning devices from an ini-

tial position, to perform the turning operation, a retracting reversing device for returning said turning devices to said position, a controlling device movable to disconnect said power-actuated devices from said turning devices, a locking device for automatically holding said turning devices in different positions of advancement, and means for releasing said locking device, substantially as described.

23. A shoe-turning machine comprising turning devices, power-actuated devices for advancing said turning devices from an initial position to perform the turning operation, means for retracting said turning devices to their initial positions, a controlling device movable to connect and disconnect said power-actuated devices from said turning devices, and means for holding said turning devices in different positions of advancement when they are disconnected from said power-actuated devices, substantially as described.

24. A shoe-turning machine comprising turning devices, power-actuated devices for advancing said turning devices from an initial position to perform the turning operation, a retracting device constantly acting in opposition to said power-actuated devices, and a controlling device for disconnecting said power-actuated devices from said turning devices, substantially as described.

25. A shoe-turning machine comprising turning devices, power-actuated devices for advancing said turning devices from an initial position to perform the turning operation, a retracting device constantly acting in opposition to said power-actuated devices, a locking device for automatically holding said turning devices in different positions of advancement, and a controlling device for said power-actuated devices, substantially as described.

26. A shoe-turning machine comprising turning devices, power-actuated devices for advancing said turning devices from an initial position to perform the turning operation, a locking device for holding said turning devices in different positions of advancement, and a controlling device movable to control both said power-actuated and said locking device, substantially as described.

27. A shoe-turning machine comprising turning devices, power-actuated devices for advancing said turning devices from an initial position to perform the turning operation, a locking device for holding said turning devices in different positions of advancement, and a controlling device movable in one direction to connect said turning devices and said power-actuated devices and in the other direction successively to disconnect said power-actuated devices and to release said locking device from said turning devices, substantially as described.

28. A shoe-turning machine comprising turning devices, power-actuated devices for advancing said turning devices from an initial position to perform the turning operation, a locking device for automatically holding said turning devices in different positions of advancement, and a controlling device movable in one direction to connect said turning devices and said power-actuated devices, and move said locking device into operative position, and movable in the opposite direction successively to disconnect said turning and said power-actuated devices, and to move said locking device into inoperative position, substantially as described. 5
29. A shoe-turning machine comprising turning devices, power-actuated devices, a controlling device for connecting said turning devices and said power-actuated devices to advance said turning devices from an initial position to perform the turning operation, means for automatically returning said turning devices to said initial position, a locking device for automatically holding said turning devices in different positions of advancement, and connections between said controlling device and said locking device for holding said locking device in an inoperative position in a certain position of said 20 controlling device, substantially as described. 25
30. A shoe-turning machine comprising turning devices, power-actuated devices for advancing said turning devices from an initial position to perform the turning operation, a controlling device for said power-actuated devices, a ratchet device for automatically holding said turning devices in different positions of advancement, and connections between said controlling device and said ratchet device for holding said ratchet device in an inoperative position in certain 35 positions of said controlling device, substantially as described. 40
31. A shoe-turning machine comprising turning devices, power-actuated devices for advancing said turning devices from an initial position to perform the turning operation, a locking device for automatically holding said turning devices in different positions of advancement, and a controlling device for disconnecting said turning devices and said power-actuated devices and holding said locking device in an inoperative position with relation to said turning 45 devices, when in one position, and for connecting said turning devices and said power-actuated devices and moving said locking device to an operative position, when moved 50 from said position, substantially as described. 55
32. A machine of the character described comprising operating devices for performing a predetermined operation, power-actuated devices, a controlling device for connecting said power-actuated devices to said operating devices to advance the latter from an initial position, and means for holding said operating devices in different positions of advancement during the performance of said operation disposed to be operated by said controlling device, substantially as described. 60
33. A machine of the character described comprising operating devices for performing a predetermined operation, power-actuated devices, a controlling device movable from an initial position to connect said power-actuated devices to said operating devices to advance the latter from their initial positions, a retracting device constantly acting in opposition to said power-actuated devices, a locking device for automatically holding said operating devices in different positions of advancement during the performance of said operation, and connections between said controlling device and said locking device for holding said locking device in inoperative position when said controlling device is in its initial position, substantially as described. 65
34. A machine of the character described, having, in combination, operating devices for performing a predetermined operation, power-actuated devices to advance said operating devices from an initial position, and means for advancing said operation by increments at the will of the operator comprising means under control of the operator for connecting the power-actuated devices 70 to the operating devices for successive periods of time and means for holding the operating devices in each new position of advancement, substantially as described. 75
35. A machine of the character described, having, in combination, operating devices for performing a predetermined operation, power-actuated devices to advance said operating devices from an initial position, a controlling device for connecting and disconnecting said power-actuated devices and said operating devices, means to return the parts to initial positions after a disconnection of the power-actuated devices and the operating devices, and a locking mechanism 80 for preventing the action of said returning means arranged to be operated by the initial connection of the power-actuated devices by means of the controlling device, substantially as described. 85
36. A machine of the character described, having, in combination, operating devices for performing a predetermined operation, power-actuated devices to advance said operating devices from an initial position, a controlling device for connecting and disconnecting said power-actuated devices and said operating devices at the will of the operator, and means, coöperating with said controlling device, for holding said operating devices in different positions of advancement during the performance of said operation, substantially as described. 90

ing devices in an intermediate position of advancement determined by successive disconnecting movements of the controlling device during said operation, substantially as described.

37. A machine of the character described, having, in combination, shoe-turning devices, power-actuated devices to advance said shoe-turning devices from an initial position, and means for advancing the turning operation by increments comprising means under control of the operator for connecting the power actuated devices to the shoe-turning devices for successive periods of time and means for holding the shoe-turning devices in each new position of advancement, substantially as described.

38. A machine of the character described, having, in combination, shoe-turning devices, power-actuated devices to advance said shoe-turning devices from an initial position, a controlling device for connecting and disconnecting said power-actuated devices and said turning devices, means to return the parts to initial position after a disconnection of the power-actuated devices and the operating devices, and a locking mechanism for preventing the action of said returning means arranged to be operated by the initial connection of the power-actuated devices by means of the controlling device, substantially as described.

39. A machine of the character described, having, in combination, shoe turning devices, power-actuated devices to advance said shoe-turning devices from an initial position, a controlling device for connecting and disconnecting said power-actuated devices and said shoe-turning devices, and means cooperating with said controlling device for holding said shoe-turning devices in intermediate positions of advancement determined by successive disconnecting movements of the controlling device during the turning operation, substantially as described.

40. A machine of the character described comprising shoe-turning means, power-actuated means, and a controlling means, movable by the operator to actuate said turning means to perform one portion of the turning operation and thereafter to connect said turning means and said power-actuated means to perform another portion of the operation, substantially as described.

41. A machine of the character described comprising shoe-turning means, power-actuated means, and a controlling means progressively movable by the operator to perform a preliminary portion of the turning operation and thereafter to connect said turning means and said power-actuated means to perform a further portion of said operation, substantially as described.

42. A shoe-turning machine comprising bending means, means adapted to be actu-

ated by the operator to move said bending means to bend the sole of the shoe preliminary to turning, turning means, power-actuating means, and means for connecting said turning means and said power-actuating means to perform the turning operation, substantially as described.

43. A shoe-turning machine comprising bending devices, means adapted to be actuated by the operator to move said devices to bend the sole of the shoe longitudinally, turning devices, and power-actuated devices movable to operate said turning devices to turn the shoe while held by said bending devices, substantially as described.

44. A shoe turning machine comprising bending means, operating means adapted to be actuated by the operator to move said bending means to bend the sole of the shoe preliminary to turning, turning means, power-actuated means movable to operate said turning means to turn the shoe while held by said bending means, and means, disposed to be operated by said operating means, for connecting said turning means and said power-actuated means, substantially as described.

45. A shoe-turning machine comprising sole bending devices, turning devices, power-actuated devices, and a controlling device, progressively movable to actuate said bending devices to bend the sole of the shoe longitudinally, and thereafter to connect said power-actuated devices and said turning devices to move the latter to turn the shoe, substantially as described.

46. A shoe-turning machine comprising sole bending devices, turning devices, power-actuated devices, and a controlling device, progressively movable to actuate said bending devices to bend the sole of the shoe longitudinally, and thereafter to connect said power-actuated devices and said turning devices to move the latter to turn the shoe, said controlling device having locking means for holding it in one of its progressive positions, substantially as described.

47. A shoe-turning machine comprising sole bending devices, turning devices, power-actuated devices, a controlling device, progressively movable to a predetermined position to actuate said bending device to bend the sole of the shoe longitudinally, means for holding said controlling device in said position, and means, disposed to be actuated by said controlling device upon further progressive movement thereof to connect said turning devices and said power-actuated devices, substantially as described.

48. A shoe turning machine comprising sole bending means, turning means, power-actuated means, a treadle, means disposed to be actuated by said treadle, when depressed to a certain position, to operate said bending means to bend the sole of the shoe pre-

51iminary to turning, and means, disposed to be operated upon further depression of the treadle, to connect said turning means and said power-actuated means and perform the turning operation, substantially as described.

49. A shoe-turning machine comprising sole bending devices, turning devices, power-actuated devices, a treadle, means disposed to be actuated by said treadle, when depressed to a certain position, to operate said bending devices to bend the sole of the shoe preliminary to turning, means for locking the treadle in said position, and means, disposed to be operated upon further depression of the treadle, to connect said turning devices and said power-actuated devices and perform the turning operation, substantially as described.

50. A shoe-turning machine comprising sole bending means, turning means, power-actuated means, and operating means movable from an initial to an intermediate position to actuate said bending means to bend the sole of the shoe preliminary to turning and movable beyond said intermediate position to control said power-actuated means, substantially as described.

51. A shoe-turning machine comprising sole bending devices, turning devices, power-actuated devices, and a controlling device movable from an initial to an intermediate position to actuate said bending means to bend the sole of the shoe preliminary to turning and movable to an extreme position from said intermediate position to connect, and from said extreme to said intermediate position to disconnect said turning devices and said power-actuated devices, substantially as described.

52. A shoe-turning machine comprising sole bending devices movable to bend the sole preliminary to turning, turning devices, power-actuated devices for advancing said turning devices from an initial position to perform the turning operation, a locking device for holding said turning devices in different positions of advancement, a controlling device movable from an initial to an intermediate position to operate said bending devices and beyond said intermediate position to control said power-actuated devices, and means disposed to be operated by said controlling device as it is moved from said intermediate to said initial position to move said locking device to an inoperative position, substantially as described.

53. A shoe-turning machine comprising sole bending devices movable to bend the sole preliminary to turning, turning devices, power-actuated devices for advancing said turning devices from an initial position to perform the turning operation, a locking device for automatically holding said turning

devices in different positions of advancement, a controlling device having means for holding said locking device in an inoperative position in the initial position of the controlling device and movable from said initial position to move said locking device to an operative position, means operated by said controlling device, as it is moved from its initial to an intermediate position, for operating said bending devices, and means for controlling said power actuated devices disposed to be operated by said controlling device as it is moved beyond said intermediate position, substantially as described.

54. A shoe-turning machine comprising forepart turning devices, means for operating said devices, and means for bending the forepart of the sole longitudinally and for holding it in bent position while said turning devices are being operated, substantially as described.

55. A shoe-turning machine comprising means for bending the forepart of the sole longitudinally at the ball, forepart turning devices, and means for operating said devices while the sole is held in bent position, substantially as described.

56. A shoe-turning machine comprising sole bending devices for bending the sole longitudinally at the ball, forepart turning devices, and means for simultaneously operating said turning devices and holding said bending devices in operative position, substantially as described.

57. A shoe-turning machine comprising sole bending devices for bending the sole longitudinally at the ball and holding it in bent position, forepart turning devices, and means for successively operating said bending devices and said turning devices, substantially as described.

58. A shoe-turning machine comprising a turning-post, and means for bending the sole forepart longitudinally about the post and for holding it in bent position while the turning operation is being performed by said post, substantially as described.

59. A shoe-turning machine comprising a turning-post, and means for bending the ball portion of the sole longitudinally about the post, adjacent the end thereof, while the shoe is held in position for turning and for holding the sole in bent position while the turning operation is being performed, substantially as described.

60. A shoe-turning machine comprising a turning-post movable longitudinally to turn the forepart of the shoe, and means for bending the sole longitudinally about said post and for holding it in bent position during the initial portion of the turning operation, substantially as described.

61. A shoe-turning machine comprising a turning-post and means for pressing the side edge portions of the sole against the

- opposite sides of said post during the preliminary portion of the turning operation, substantially as described.
62. A shoe-turning machine comprising a forepart turning-post, a sole bending device movable to press the sole about opposite sides of said post adjacent its end, and means for moving said post longitudinally while said bending device is in operative position, substantially as described.
63. A shoe-turning machine comprising a forepart turning-post, and a sole bending device having means for moving the same transversely of the post to press the sole about opposite sides thereof and for holding the sole in bent position while the turning operation is being performed, substantially as described.
64. A shoe-turning machine comprising a forepart turning-post, a sole-bending device having means for moving the same transversely of the post to press the sole about opposite sides thereof, and means for moving said bending device longitudinally of the post away from the end thereof while holding the sole in bent position during the performance of the turning operation, substantially as described.
65. A shoe-turning machine comprising a forepart turning-post, a bending device for bending the sole longitudinally about the post adjacent the end of the post, and means for simultaneously moving said post longitudinally in one direction to perform the turning operation and said bending device in the opposite direction while holding the sole in bent position, substantially as described.
66. A shoe-turning machine comprising a forepart turning-post, a pair of sole-bending devices disposed at opposite sides of and in front of said post, and means for moving said devices simultaneously to engage the side edge portions of a shoe forepart held longitudinally of said post to bend the same longitudinally and hold the same in bent position during the preliminary portion of the turning operation, substantially as described.
67. A shoe-turning machine comprising a forepart turning-post, and a pair of fingers extending longitudinally of said post and movable from positions in front of said post to points adjacent the opposite sides thereof to bend longitudinally the sole of a shoe held on the post in position to be turned, substantially as described.
68. A shoe-turning machine comprising a forepart turning-post, a pair of sole-bending devices, and means for moving said devices from positions in front of, and at opposite sides of said post, convergently toward the opposite sides of the post, substantially as described.
69. A shoe-turning machine comprising a forepart turning-post, a pair of sole-bending fingers extending longitudinally of and approximately parallel to said post, and means for moving said fingers into close proximity to opposite sides of the post, substantially as described.
70. A shoe-turning machine comprising a forepart turning-post, a clamp for engaging opposite sides of the rear part of the sole adjacent one side of the post, and means for moving said clamp away from the end of the post to turn the shoe, substantially as described.
71. A shoe-turning machine comprising a longitudinally movable forepart turning-post, an independently supported clamp for engaging opposite sides of the rear-part of the sole to hold the same against the action of the post as it is moved to turn the shoe and means controlled by the machine for first closing the clamp and then moving the forepart turning-post, substantially as described.
72. A shoe-turning machine comprising a forepart turning post, a clamp for engaging opposite sides of the rear part of the sole and means for moving the clamp to draw the sole over the end of the post to turn the shoe, substantially as described.
73. A shoe-turning machine comprising a fore-part turning post, a clamp having one member supported adjacent the end of said post, and at one side thereof, in position to engage one side of the rear part of the sole, an arm having the other clamp member mounted thereon and movable to carry said clamp member transversely of the post into engagement with the other side of the sole to clamp the same between said members, and means for moving said clamp away from the end of the post, substantially as described.
74. A shoe-turning machine comprising a fore-part turning post, an arm supported independently of said post, extending longitudinally of the post at one side thereof and adjacent thereto, a clamp having one member supported at the end of said arm in position to engage one side of the rear part of the sole, another arm having the other clamp member supported thereon and movable to carry said member transversely of the post into engagement with the other side of the sole, and means for moving said arms away from the end of the post, substantially as described.
75. A shoe-turning machine comprising a fore-part turning post, a clamp having one member disposed adjacent one side of the post in position to engage one side of the sole, and having the other member movable to engage the opposite side of the sole, and means for moving said clamp longitudinally of the post and away from the end thereof, substantially as described.

76. A shoe-turning machine comprising a vertically disposed fore-part turning post, a clamp having one member disposed adjacent one side of the post and adjacent and below its end, in position to engage one side of the sole, and having the other member movable transversely of the post to engage the opposite side of the sole and means for moving said clamp members downwardly while in engagement with the sole, substantially as described.
77. A shoe-turning machine comprising a forepart turning-post, means for moving said post longitudinally, an independently supported clamp having one member disposed adjacent one side of the post in position to engage one side of the rear portion of the sole and having the other member movable to engage the opposite side thereof to hold the same therebetween against the action of the post in turning the shoe and means controlled by the machine for first closing the clamp and then moving the fore-part turning-post, substantially as described.
78. A shoe-turning machine comprising a vertically disposed forepart turning-post, a clamp having one member disposed adjacent one side of the post and below its upper end to engage one side of the sole, and having the other member movable to engage the opposite side of the sole, and means for simultaneously moving the post upwardly and the clamp downwardly, substantially as described.
79. A shoe-turning machine comprising a forepart turning-post, a clamp having one member thereof supported adjacent the end of said post at one side thereof in position to engage one side of the rear part of the sole, an arm having the other clamp member mounted thereon, and movable to carry its clamp member transversely of the post into engagement with the other side of the sole and clamp the same therebetween, and means for moving said post longitudinally to turn the shoe while the sole is held by said clamp, substantially as described.
80. A shoe-turning machine comprising a vertically disposed forepart turning-post, an arm supported independently of said post, extending vertically at one side thereof, in close proximity thereto, and terminating adjacent the upper end thereof, a clamp having one member supported on the upper end of said arm in position to engage one side of the rear part of the sole, as the sole is bent over the end of the post in position for turning, a movable arm having the other clamp member supported thereon and adapted to carry the same into engagement with the other side of the sole, and means for moving said post upwardly to turn the forepart of the shoe while the rear-part of the sole is held by said clamp, substantially as described.
81. A shoe-turning machine comprising a forepart turning-post, an arm extending longitudinally of said post to a point adjacent the end thereof, a clamp having one member mounted on the end of said arm and having a clamping face at the opposite side thereof from said post, and a support having the other member of said clamp thereon and movable to clamp the sole between said members, and means for causing relative movement of the post and clamp to turn the shoe, substantially as described.
82. A shoe-turning machine comprising a forepart turning-post, an arm extending longitudinally of said post to a point adjacent the end thereof, said arm having a bearing face adapted to engage the side of the post, a clamp having one member mounted on the end of said arm and having a clamping face at the opposite side thereof from said post, and a support having the other member of said clamp thereon and movable to clamp the sole between said members, and means for causing relative movement of the post and clamp to turn the shoe, substantially as described.
83. A shoe-turning machine comprising a forepart turning-post, a clamp supported independently of said post having one member located at the rear side of the post adjacent the end thereof, an arm having the other member of the clamp supported thereon and movable to carry said member from a position remote from the other member and into operative engagement therewith, and means for causing relative movement of said post and clamp to turn the shoe, substantially as described.
84. A shoe-turning machine comprising a forepart turning-post, a clamp having one member thereof supported adjacent the end of said post, said member having a sole engaging face at the opposite side thereof from the post extending longitudinally thereof and having a projection thereon for causing a bend about an axis extending transversely of the sole, and the other member of said clamp being movable to engage said first named member adjacent said projection, and means for causing relative movement of said post and clamp to turn the shoe, substantially as described.
85. A shoe-turning machine comprising a forepart turning-post, a clamp having one member thereof supported adjacent the end of said post, said member having sole engaging teeth on the opposite side thereof from the post, the other member of said clamp being movable to hold the sole in engagement with said teeth, and means for causing relative movement of said clamp and post to turn the shoe, substantially as described.
86. A shoe-turning machine comprising a fore-part turning post, a toe gage at one side

of the post, and means to move the post relatively to the toe gage, substantially as described.

87. A shoe-turning machine comprising a forepart turning-post, and a toe-gage at one side of the post adjustable longitudinally thereof, substantially as described.

88. A shoe-turning machine comprising a forepart turning-post, a sole-bending device for bending the forepart of the sole longitudinally at one side of the post and for holding it thereagainst, a retaining device for engaging the rear part of the shoe, at the other side of the post, to hold the same against longitudinal movement, while the sole is bent over the end thereof, and means for moving said post longitudinally to turn the shoe while engaged by said devices, substantially as described.

89. A shoe-turning machine comprising a forepart turning-post, a sole-bending device movable to bend the sole longitudinally about one side of the post, a sole-clamping device movable to clamp the sole between its members at the opposite side of said post, and means for successively operating said bending device and said clamping device and then moving said post to perform the turning operation, substantially as described.

90. A shoe-turning machine comprising a shaft, a forepart turning-post, connections between said post and shaft for moving said post longitudinally on partial rotation of the shaft, a clamp having one member disposed adjacent the post, and means, disposed to be operated by the shaft as it rotates to move the post, for moving the other member into operative relation therewith, substantially as described.

91. A shoe-turning machine comprising a shaft, a forepart turning-post, connections between said post and shaft for moving said post longitudinally on partial rotation of the shaft, a clamp for engaging the sole rear-part of a shoe held on the post in position to be turned, and connections between said shaft and clamp for moving the members thereof into operative relation upon the initial movement of the shaft to move the post, substantially as described.

92. A shoe-turning machine comprising a shaft, a forepart turning-post, connections between said post and shaft for moving said post longitudinally on partial rotation of the shaft, a clamp for engaging the sole rear-part of a shoe held on the post in position to be turned, and means, operated by said shaft as it rotates to move said post in one direction, for moving the clamp members into operative relation and thereafter moving them in the opposite direction, substantially as described.

93. A shoe-turning machine comprising a shaft, a forepart turning post, connections

between said shaft and post for causing longitudinal movement of the post on partial rotation of the shaft, a clamp having one member thereof supported independently of the post adjacent the end of said post, a lever having the other clamp member at one end thereof and disposed at one side of said arm, and connections between the opposite end of said lever and said shaft for swinging said lever to move its member into operative relation with the other clamp member, as the shaft is rotated to move the post, substantially as described.

94. A shoe-turning machine comprising a shaft, a forepart turning post, connections between said shaft and post for causing longitudinal movement of the post on partial rotation of the shaft, a clamp composed of a longitudinally movable arm extending longitudinally of said post and having one clamp member on one end thereof, and a lever having the other clamp member on one end thereof, a fulcrum for engaging an intermediate portion of said lever and permitting longitudinal movement thereof, and connections between said shaft and the opposite ends of said lever and arm for swinging said lever into operative relation with said arm and moving said arm and said lever in one direction as the post is moved in the opposite direction, substantially as described.

95. A shoe-turning machine comprising a fore-part turning post, a sole bending device for bending the forepart of the sole longitudinally at one side of the post, and for holding it closely adjacent thereto, an engaging device for the rear part of the shoe at the other side of the post when the sole is bent over the end thereof, and means for moving said engaging device away from the end of the post while the shoe is engaged by said bending device, substantially as described.

96. A shoe-turning machine comprising a fore-part turning post, a sole-bending device movable to bend the sole longitudinally about one side of the post, a clamping device movable to clamp the sole between its members at the opposite side of said post, and means for operating said bending device and moving said clamping device to clamp the sole and thereafter moving said clamping device away from the end of the post while the fore-part is engaged by said bending device, substantially as described.

97. A shoe-turning machine comprising operating means, a forepart turning post, and a clamp having one member disposed adjacent the post and means, disposed to be actuated by said operating means, for moving the other member of said clamp into operative relation therewith and for thereafter moving said clamp longitudinally of

the post away from the end thereof, substantially as described.

98. A shoe-turning machine comprising operating means, a forepart turning post, a 5 clamp for engaging the sole rear part of a shoe held on the post in position to be turned, and means, disposed to be actuated by said operating means, for moving said clamp members into operative relation and 10 thereafter to move said members longitudinally of the post and away from the end thereof, substantially as described.

99. A shoe-turning machine comprising an operating device, a forepart turning 15 post, a clamp having one member thereof supported independently of the post, adjacent its end, a lever having the other clamp member at one end thereof, and connections between the opposite end of said 20 lever and said operating device for swinging said lever to move its clamp member into operative relation with the other clamp member, and thereafter to move the clamp longitudinally of the post away from the 25 end thereof, substantially as described.

100. A shoe-turning machine comprising an operating device, a forepart turning post, a clamp composed of a longitudinally movable arm extending longitudinally of 30 said post and having one clamp member thereon, and a lever having the other clamp member at one end thereof, a fulcrum for engaging the intermediate portion of said lever and permitting longitudinal movement 35 thereof, and means disposed to be actuated by said operating device for successively swinging said lever into clamping relation with said arm and for thereafter moving said lever and arm away from the 40 end of the post, substantially as described.

101. A shoe-turning machine comprising a forepart turning post, a clamp for holding the sole rear part of a shoe placed on said post in position to be turned, power actuated means for moving the members of the 45 clamp into clamping relation, and means adapted to be moved by the operator for moving one of said members out of engagement with the shoe, substantially as described.

102. A shoe-turning machine comprising a forepart turning-post, a clamp for holding the sole rear part of a shoe held on said post in position to be turned, power- 50 actuated means for moving said post longitudinally and the members of said clamp into operative relation, and means adapted to be moved by the operator for releasing said members, substantially as described.

103. A shoe-turning machine comprising a turning post, a pressure plate at one side of the post in position to hold the shoe forepart in proximity thereto, an engaging device for the shoe rearpart at the opposite

side of the post, and means for moving said 65 engaging device longitudinally of the post to turn the shoe, substantially as described.

104. A shoe-turning machine comprising a turning-post, a pressure plate supported at one side of the post in position to hold 70 the shoe forepart in proximity thereto, a clamp for engaging the rearpart of the shoe at the opposite side of the post, and means for moving said clamp longitudinally of the post to turn the shoe, substantially as 75 described.

105. A shoe-turning machine comprising a turning post, a spring actuated pressure device supported at one side of the post in position yieldingly to hold the shoe forepart in proximity to the post, and means for turning the shoe on the post while held by said pressure device, substantially as described.

106. A shoe-turning machine comprising 85 a forepart turning post, and a holding device supported at one side thereof at a distance therefrom to permit both the sole and upper of the forepart of the shoe to be inserted between said device and the post, 90 and means for pressing said device toward said post to hold the forepart of the shoe closely adjacent the post as the turning operation is performed, substantially as described.

107. A shoe-turning machine comprising a forepart turning post, means for holding the shoe forepart against transverse movement at one side of the post, and means disposed to engage the rearpart of the shoe at 100 the opposite side of said post and movable to draw the shoe over the end of the post, substantially as described.

108. A shoe-turning machine comprising a forepart turning post, an engaging device 105 for pressing the shoe forepart into close proximity to one side of the post and disposed to permit the shoe to be withdrawn from between the same and the post, and means for drawing the shoe over the end of 110 the post to turn the shoe as its forepart is withdrawn from between the engaging device and the post, substantially as described.

109. A shoe-turning machine comprising a turning-post, a tool supported at one side 115 of the post and in position to hold the shoe forepart in proximity to the post, means at the opposite side of the post, for holding the shoe rear part against longitudinal movement in the direction in which the 120 post is moved, and means for moving the post longitudinally to turn the shoe, substantially as described.

110. A shoe-turning machine comprising a turning-post, a tool supported independently of the post at one side thereof and in position to hold the shoe forepart in proximity thereto, means at the opposite 125

side of the post, for holding the shoe rear part against longitudinal movement in the direction in which the post is moved, and means for moving the post longitudinally to 5 turn the shoe, substantially as described.

111. A shoe-turning machine comprising a turning-post, a spring-actuated pressure device supported at one side of the post and in position yieldingly to hold the shoe forepart 10 in proximity to the post, a holding device for engaging the shoe rear part at the opposite side of the post, and means for moving the post longitudinally to turn the shoe while engaged by said devices, substantially as described.

112. A shoe-turning machine comprising a forepart turning-post, and a holding plate supported at one side thereof, and in proximity thereto, said plate extending longitudinally of the post and having an engaging face at its side next the post for engaging the vamp of the shoe, substantially as described.

113. A shoe-turning machine comprising a turning-post having a holding plate supported at one side of the post, and in proximity thereto, said plate extending longitudinally of the post, and having a transversely and inwardly curved engaging face 30 at its side next the post, substantially as described.

114. A shoe-turning machine comprising a turning-post having a holding plate supported at one side of the post, and in proximity thereto, said plate extending longitudinally of the post and having an engaging face at its side next the post, said face extending divergently with relation to the post at its end next the end of the post, substantially as described.

115. A shoe-turning machine comprising a turning-post having a holding plate supported at one side of the post, and in proximity thereto, said plate extending longitudinally of the post and having an engaging face at its side next the post, said face being outwardly curved at its side edges and inwardly curved at its middle portion, substantially as described.

116. A shoe-turning machine comprising a forepart turning-post, a holding plate supported at one side thereof, and in proximity thereto, said plate extending longitudinally of the post and having an engaging face at 55 its side next the post for engaging the vamp of the shoe, and means constructed to permit adjustment of the plate longitudinally of the post, substantially as described.

117. A shoe-turning machine comprising a forepart turning-post, means for holding the forepart of the shoe against transverse movement adjacent one side of the post and means for holding the rear part of the shoe against longitudinal movement adjacent the

other side of the post, while the shoe is bent over the end of the post, and means for causing relative movement of said post and said rear part holding means to turn the shoe, substantially as described.

118. A shoe-turning machine comprising a turning-post, means for holding a shoe forepart against transverse movement at one side of the post, and its rear-part against longitudinal movement at the opposite side of the post, and means for moving the post longitudinally to perform the turning operation, substantially as described.

119. A shoe-turning machine comprising a forepart turning-post, an engaging device for pressing the shoe forepart against one side of said post and disposed to permit the shoe to be withdrawn from between the same and the post, a holding device for engaging the rear portion of the shoe when bent over the end of the post, and means for moving said post longitudinally along the shoe bottom to turn the shoe while its forepart is held against the post by said engaging device and its heel-part is held against longitudinal movement in the direction in which the post is moved, substantially as described.

120. A forepart turning machine, having, in combination a turning-post to enter the shoe as the turning operation progresses, and means to engage the forepart and bend the sole of the shoe longitudinally preliminarily to the commencement of the turning operation, substantially as described.

121. In a shoe-turning machine, shoe turning tools, a controlling device progressively movable from an initial to an intermediate position and from said intermediate to an extreme position to cause said tools to perform successive portions of the turning operation, means for returning said controlling device to said initial position, means for automatically locking said controlling device when in said intermediate position, and means for rendering said locking device inoperative when said controlling device is returned from said extreme to said initial position, substantially as described.

122. A shoe-turning machine comprising a sole bending device, a controlling device, movable from an initial to an intermediate position to operate said bending device, and from said intermediate position to an extreme position, to perform a further portion of the turning operation, means for automatically locking said controlling device against retraction when in said intermediate position, and means for rendering said locking means inoperative when said controlling device is moved toward said extreme position from said intermediate position, substantially as described.

123. A machine for operating on shoes,

- having, in combination, operating tools, a controlling device progressively movable from an initial to an intermediate position and from said intermediate to an extreme 5 position to cause said tools to perform successive operations on the shoe, returning means for said controlling device, a locking device for automatically holding said controlling device against retraction when in 10 said intermediate position, and means for holding said locking device in an inoperative position when said controlling device is moved from said extreme to said initial position, substantially as described.
- 15 124. A shoe-turning machine comprising sole-bending devices, a controlling device having returning means and movable from an initial to an intermediate position, to actuate said bending devices, means for locking 20 said controlling device against retraction when in said intermediate position, turning devices, power-actuated devices, and means disposed to be operated upon advancement of said controlling device beyond 25 said intermediate position to connect said turning and said power-actuated devices to perform the turning operation, substantially as described.
125. In a shoe-turning machine comprising sole-bending devices, a controlling device having returning means and movable from an initial to an intermediate position, to actuate said bending devices, a locking device for automatically holding said controlling device against retraction when in 30 said intermediate position, turning devices, power-actuated devices, means disposed to be operated upon advancement of said controlling device beyond 35 said intermediate position, to connect said turning and said power-actuated devices to perform the turning operation, and a trip device for said locking device disposed to operate upon the return movement of said controlling device 40 to permit the same to return to its initial position, substantially as described.
126. A machine of the character described comprising operating devices, power-actuated tools, a controlling device movable from an initial to an intermediate position to cause said operating tools to perform one portion of the operation, and movable from 50 said intermediate to an extreme position to connect said power actuated devices to said operating tools, to cause the latter to perform another portion of the operation, a locking device for holding said operating tools in different positions of advancement, and means, disposed to be operated by said 55 controlling device, for moving said locking device to an operative position as said controlling device is moved from said intermediate to said extreme position, and for moving said locking device to an inopera- 60 tive position when said controlling device is moved from said intermediate to said initial position, substantially as described.
127. A shoe-turning machine comprising turning devices, power-actuated devices, a controlling device movable from an initial to an intermediate position to cause said turning devices to perform a preliminary portion of the operation and movable from 65 said intermediate position to an extreme position to connect said power-actuated devices and said turning devices to cause the latter to perform the remaining portion of the operation, a locking device for holding said turning devices in different positions of advancement, and means disposed to be operated by said controlling device for moving said locking device to an operative position as said controlling device is moved from said intermediate to said extreme position, and for moving said locking device to an 70 inoperative position when said controlling device is moved from said intermediate to its initial position, substantially as described.
128. A machine of the character described comprising operating tools for performing a predetermined operation, power-actuated devices, a controlling device movable to connect said power-actuated devices and said operating tools to advance the latter from 75 an initial position to perform said operation and to disconnect the same in different positions of advancement of said operating tools, and means for returning said operating tools to said initial position from the different 80 positions to which they may be advanced by said power-actuated devices, substantially as described.
129. A shoe-turning machine comprising turning devices, power-actuated devices, and a controlling device movable to connect said power-actuated devices and said turning devices to advance said turning devices from an initial position to perform the turning operation, and to disconnect the same in 85 different positions of advancement of said turning devices, and means for returning said turning devices to said initial position from the different 90 positions to which they may be advanced by said power-actuated devices, substantially as described.
130. A machine of the character described comprising operating tools for performing a predetermined operation, power actuated devices, a controlling device for connecting said power-actuated tools and said operating devices to advance the latter from an initial position, means for holding said operating tools in different positions of advancement during the performance of said 100 operation, disposed to be controlled by said controlling device, and a retracting device disposed to reverse the movement of the 105

parts when disconnected from said power-actuated devices to return the same to their initial position from any position to which they may have been advanced, substantially 5 as described.

131. A machine for turning the foreparts of shoes, having, in combination, a forepart turning post, means for advancing said post toward the toe of the shoe to turn the 10 forepart, and means in addition to said first named means for proportioning the advance of the post in accordance with the size of the shoe being operated upon, substantially as described.

132. A machine for turning the foreparts of shoes, having, in combination, a forepart turning post, means for advancing said post toward the toe of the shoe to turn the forepart, and means, controlled by the machine, 20 for stopping the advance of the post when it has reached a predetermined position within the forepart, substantially as described.

133. A machine for turning the foreparts 25 of shoes, having, in combination, a forepart turning post, means for positioning the shoe with the end of the post substantially at the ball line of the sole, automatic means for advancing said post toward the toe of the 30 shoe, and automatically operating mechanism for limiting the extent of the advance movement within the forepart of the shoe, substantially as described.

134. A shoe-turning machine, having, in 35 combination, turning devices, means for advancing said turning devices from an initial position to perform the turning operation, and additional means under control of the operator for stopping the advance of the 40 turning devices at will and locking them in any desired position of advancement, substantially as described.

135. A machine for turning the foreparts of shoes, having, in combination, a fore-

part turning post, devices for holding the shoe with its sole bent about the end of said post, and means for relatively moving the shoe and post to turn the forepart over the post, substantially as described.

136. A machine for turning the foreparts 50 of shoes, having, in combination, a forepart turning post, a heel clamp, a device for holding the forepart against the side of the post, and means for relatively moving the heel clamp and post to draw the forepart 55 from its holding device and turn it over the post, substantially as described.

137. A machine for turning the foreparts 60 of shoes, having, in combination, a forepart turning post, a heel clamp, a device for holding the forepart bent about the end of the post with the toe pointing toward the heel, and means for advancing the post to strip the forepart from said device and turn it over the post, substantially as described. 65

138. A machine for turning the foreparts 70 of shoes, having, in combination, a forepart turning post, means under control of the operator for engaging the forepart and holding it bent about the end of the post, and automatic means for thereafter advancing the post to turn the forepart, substantially as described.

139. A shoe-turning machine, having, in 75 combination, a forepart turning post, means to advance the post to turn the forepart, and a toe gage at one side of said post mounted for movement relatively to the post to a position to engage the toe of the shoe preliminary to the advance of the post to turn 80 the forepart, substantially as described.

In testimony whereof, I have signed my name to this specification, in the presence of two subscribing witnesses.

GEORGE B. GARDNER.

Witnesses:

L. H. HARRIMAN,
H. B. DAVIS.

Copies of this patent may be obtained for five cents each, by addressing the "Commissioner of Patents, Washington, D. C."

It is hereby certified that in Letters Patent No. 1,140,454, granted May 25, 1915, upon the application of George B. Gardner, of Haverhill, Massachusetts, for an improvement in "Shoe-Turning Machines," errors appear in the printed specification requiring correction as follows: Page 1, line 64, strike out the words "by the means"; page 10, line 67, strike out the word "reversing"; page 19, line 121, for the word "tools" read *devices*; same page, line 122, for the word "devices" read *tools*; page 20, line 32, after the word "movement" insert the words *of the post*; and that the said Letters Patent should be read with these corrections therein that the same may conform to the record of the case in the Patent Office.

Signed and sealed this 27th day of July, A. D., 1915.

[SEAL.]

R. F. WHITEHEAD,
Acting Commissioner of Patents.
